UNITED STATES PATENT OFFICE.

GEORGE STAGG GALLAGHER, OF NEW YORK, N. Y., ASSIGNOR TO HIMSELF, RUPERT L. JOSEPH, AND FRANK E. BURROWS, OF NEW YORK, N. Y.

SYSTEM FOR OPERATING STOCK-BOARDS.

SPECIFICATION forming part of Letters Patent No. 752,059, dated February 16, 1904.

Application filed April 29, 1903. Serial No. 154,783. (No model.)

To all whom it may concern:

Be it known that I, GEORGE STAGG GALLAGHER, a citizen of the United States, residing in the borough of Manhattan, city, county, and State of New York, have invented an Improvement in Systems for Operating Stock-Boards, of which the following is a specification.

Heretofore it has been customary to place stock-quotations on stock-boards manually; and the object of my invention is to provide a system whereby stock-quotations may be printed electrically and simultaneously upon one or more stock-boards.

According to the present invention my improved system consists in a single stock-board or series of similar duplicate stock-boards, each stock-board comprising a series of paper strips for quotations of different stocks, an electrical printing-machine for each paper strip, an operating device for the printing-machines, a circuit-selector, a circuit-maker, means for actuating the same, and means for short-circuiting any stock-board in the system.

In the drawings, Figure 1 is a diagrammatic view of my system of operating stock-boards. Fig. 2 is a front elevation of a stock-board, and Fig. 3 is a transverse vertical section of the same.

a represents a stock-board, the lower part of which is adapted to receive a number of electric printing instruments, preferably as shown and described in my copending application, Serial No. 154,782, for Letters Patent for electrical printing-machines. The face of the stock-board is preferably divided into a number of vertical spaces *b*, equal in number to the printing instruments used and each adapted to receive the paper strip *c* from one of the instruments, every stock to be quoted on the board having its own instrument, paper strip, and space in the board. I also employ a circuit-selector *d* and an operating device *e* for the printing-machines adapted to rapidly make and break electric circuits and to momentarily keep a circuit closed, as shown and described in my copending application,

Serial No. 154,781, for Letters Patent for operating devices for electrically - controlled mechanism.

2 and 3 represent electromagnets, one pair for each stock-board and placed in series in the circuit, which may be closed by the selector *d* in any predetermined position. Each electromagnet 3 actuates a latch 4 to throw a switch 5, closing the independent circuit *h* of a small motor 6. The position of the contact 7 is regulated by a governor 8 on the shaft of the motor 6, so that when the motor is not running the contact 7 is brought against the terminals 9 10.

f represents a circuit-maker, one of which is employed for each stock-board in the system. The circuit-maker comprises a contact-arm 11, revolved by an escapement 12, which is actuated by the magnet 2 through the arm 13. As the contact-arm 11 revolves it bears successively upon contacts 14, which correspond in number with the spaces on the stock-board, each contact 14 being connected by a conductor 15 to one of the terminals of one printing instrument, the other terminal of the instrument being connected to the operating device *e* by means of lines 16 and 17. The contact-arm 11 is connected with the terminal 9 by the conductor 18, and the terminal 10 is connected to the line 17 by a conductor 19, the terminal 9 being connected to the line 20, leading to the next board, by a conductor 21. One generator *i* may be employed to supply the current for the entire system.

The number of positions in which the selector *d* may be stopped corresponds to the number of instruments employed in the boards, and consequently to the number of contacts on the circuit-makers *f*. The circuit through the magnets 2 is rapidly made and broken by the selector *d* energizing and de-energizing the magnet 2, thereby actuating the escapement to revolve the contact-arm 11. Hence when the circuit is closed the contact-arm stops on the contact corresponding to the position in which the selector *d* was stopped

and connects the instrument corresponding with this position with the operating device *e*. The number of positions in which the operating device *e* may be stopped corresponds with 5 the number of characters which each instrument is capable of printing, and when the operating device *e* is stopped the instrument corresponding to the stopped position of the selector *d* prints the character corresponding to 10 the stopped position of the operating device *e*, provided the switch 5 is closed and the contact 7 is not in connection with the terminals 9 and 10. If the switch 5 is open and the contact 7 in connection with the terminals 9 and 15 10, the stock-board will be short-circuited through these parts and the conductors 19 and 21.

In the operation of the system the selector *d* is stopped at the position of the stock to be 20 quoted. This stops the arm 11 on the desired contact 14, throws the switches 5, and disconnects the contact 7 from the terminals 9 and 10. The operating device *e* is then stopped successively in the positions corresponding to 25 the characters employed in quoting the stock, the stopping of the operating device *e* causing the instrument with which it is in circuit to print the characters corresponding to the stops made by the operating device.

30 In Fig. 3, 22 represents the type-wheel of the printing instrument; 23, the striking-hammer; 24, the magnet for actuating the hammer; 25, the drum upon which the paper strip *c* is wound, and 26 the drum from which the 35 same is unwound.

I claim as my invention—

1. A stock-board-operating system, comprising a series of movable paper strips for quotations of different stocks, an electrical 40 printing instrument for each paper strip, a circuit-maker for successively completing the electric circuit through the several printing instruments, a circuit-selector for controlling said circuit-maker and an operating device for 45 controlling the printing instrument.

2. A stock-board-operating system, comprising a plurality of stock-boards each consisting in a frame, a number of electrical printing instruments and a movable paper strip for 50 each printing instrument, a circuit-maker for successively completing the electric circuit through the several printing instruments, a circuit-selector for controlling the said circuit-maker and an operating device for controlling the printing instrument.

3. A stock-board-operating system, comprising a plurality of stock-boards, each consisting in a frame, a number of electrical printing instruments and a movable paper strip for 60 each printing instrument, a circuit-maker for successively completing the circuit through the several printing instruments and having a contact for each printing instrument em-

ployed, means for actuating said circuit-maker to successively complete the electric circuit 65 through each printing instrument, a selector for controlling the said circuit-maker to determine which printing instrument is to be employed, and an operating device for determining which characters the printing instrument selected is to print.

4. A stock-board-operating system, comprising a plurality of stock-boards, each consisting in a frame, a number of electrical printing instruments, a movable paper strip for 75 each printing instrument, a circuit-maker for successively completing the circuit through the several printing instruments and having a contact for each printing instrument employed, an escapement mechanism and an electromagnet for actuating said circuit-maker to successively complete the circuit through each printing instrument, a selector for controlling the said circuit-maker to determine which printing instrument is to be employed, 80 and an operating device for determining which character the printing instrument selected is to print.

5. A stock-board-operating system, comprising a plurality of stock-boards each consisting in a frame, a number of electrical printing instruments and a movable paper strip for each printing instrument, a circuit-maker for successively completing the electric circuit through the several printing instruments, a 90 circuit-selector for controlling the said circuit-maker, an operating device for controlling the printing instruments, and means for short-circuiting any stock-board in the system.

6. A stock-board-operating system, comprising a plurality of stock-boards, each consisting in a frame, a number of electrical printing instruments and a movable paper strip for each instrument, a circuit-maker for successively completing the electric circuit through 105 the several printing instruments and having a contact for each printing instrument employed, a contact-arm adapted to bear on said contacts, an escapement mechanism for rotating said contact-arm, a selector for controlling 110 said circuit-maker to determine which instrument is to be employed, a magnet in the circuit of said selector and adapted to actuate said escapement mechanism, and an operating device for determining which characters the 115 printing instrument is to print.

7. A stock-board-operating system, comprising a plurality of stock-boards, each consisting in a frame, a number of electrical printing instruments and a movable paper strip 120 for each printing instrument, a circuit-maker for successively closing the electric circuit through each printing instrument and having a contact for each printing instrument employed, a contact-arm adapted to bear on said contacts, an escapement mechanism for rotat-

ing said contact-arm, a selector for controlling said circuit-maker to determine which printing instrument is to be employed, a magnet in the circuit of said selector adapted to actuate said escapement mechanism, an operating device for determining which character the printing instrument is to print, and means for short-

circuiting any of the stock-boards in the system.

Signed by me this 25th day of March, 1903. ^{to}
GEORGE STAGG GALLAGHER.
